SHUTTLE AND FILLING CARRIER FOR LOOMS

Wallace I. Stimpson, Hopedale, Mass., assignor to Draper Corporation, Hopedale, Mass., a corporation of Maine

Application March 19, 1934, Serial No. 716,247

4 Claims. (Cl. 139—207)

The present invention pertains to loom shuttles, and has more particular reference to shuttles of the type adapted for use in automatic bobbin changing looms.

5 Shuttles of the type mentioned are customarily provided with opposed spring jaws which are notched to receive rings mounted on the butt of a filling carrier, such as a bobbin or the like. The filling carrier is automatically replaced by a 10 new one by mechanism which drives the new filling carrier down into the shuttle from the top thereof, the incoming filling carrier engaging the old one and ejecting it out through the bottom of the shuttle. It will thus be seen that the rings 15 of the incoming filling carrier engage the rings of the filling carrier which is being ejected.

It has been found that in order to prevent mutilation of the butts of the filling carriers during transfer, and in order to insure effective placement of the filling carrier in the jaws of the shuttle spring, the rings on the butt of the filling carrier should be positioned quite close together. Two such rings, closely spaced, were found to not hold the filling carrier sufficiently rigid, and accordingly the accepted practice has been to provide three such rings.

Shuttles of the type mentioned, that is, shuttles wherein the spring jaws have been provided with three or four notches for receiving three 30 rings on a filling carrier, have been open to the objection that even the three rings and notches do not hold the filling carrier as firmly as they should due to unavoidable irregularities in both the spring jaws and the filling carrier. The 35 failure to hold the filling carrier firmly contributes materially to filling breakage and has thus been the cause of considerable wasted time and expense.

It is the principal object of my invention to 40 provide, in an automatic loom shuttle of the type mentioned, means including opposed spring jaws in the shuttle and three rings on the filling carrier which are so constructed as to hold the filling carrier with the desired firmness.

45 Further objects will become apparent as the description proceeds.

Two embodiments of my invention are illustrated on the accompanying drawing. Referring to said drawing:

50 Fig. 1 is a plan view of the spring end of the shuttle;

Fig. 2 is a view similar to Fig. 1 but showing the second embodiment;

Fig. 3 is a detail, partly in section, of one of 55 the spring jaws of Fig. 2; and

Fig. 4 is a view of the spring jaws and filling carrier of Fig. 1, the spring jaws being shown in section.

Referring first to Figs. 1 and 4, the shuttle 1 is provided with a cavity 2 within which is housed the filling carrier, as bobbin 3. The left hand end of the shuttle is recessed to receive opposed spring jaws 4 and 5 which extend along the walls of the cavity and which may have their shank portions integrally joined as shown. A spring cover 6, 60 provided with an inclined bobbin guide 7 is firmly secured to the spring by means of a vertical bolt or screw 8. The spring assembly is secured in the shuttle body by means of a horizontal bolt 9. The shuttle and spring as thus far described 70 are not of the present invention and it will be apparent that my invention is not limited to the particular form of shuttle and spring assembly shown.

The jaws 4 and 5 are each provided with parallel vertical notches or grooves 11, 11 which notches are of uniform depth and are otherwise substantially identical. Only three such notches in each jaw are required but it is preferred to provide four, in order that the bobbin may still 80 be properly held if it is misplaced toward its tip during the transferring operation.

In the embodiment under discussion the filling carrier is modified to incorporate the features of my invention. To this end, the butt 12 of the 85 bobbin is provided with three parallel, circumferential rings 13, 14 and 15 which are spaced apart the same distance as the spacing of the notches 11 in the spring jaws. It will be noted that the rings are of the same thickness and the space 90 between adjacent rings is substantially narrower than the thickness, or diameter, of the stock of which the rings are formed. These rings are made of spring steel stock, preferably of circular cross-section.

The two outer rings, 13 and 15, are of substantially the same external diameter and engage in the corresponding notches in the spring jaws. The center ring 14 has a smaller external diameter and consequently does not at any time 100 engage in any of the notches. The smaller external diameter of the center ring is preferably provided by making the ring of the same diameter of stock as the outer rings but embedding it in a deeper groove in the butt of the bobbin.

It will be seen that the construction just described is not subject to the above enumerated disadvantages of the prior art. That is, the rings 13, 14 and 15 are so closely spaced that during transfer the rings on an incoming bobbin cannot 110

cause the bobbin to jump endwise, nor can they mutilate the wood of the bobbin butt. The two outside rings 13 and 15 are spaced apart a sufficient distance that they firmly hold the bobbin butt. The two outside rings 13 and 15 are spaced apart a sufficient distance that they firmly hold the bobbin in the desired position. Then, since the center ring is smaller in external diameter than the outer rings and does not engage the 10 spring jaws, slight irregularities in the spring jaws, notches or rings will not in any way render the grip of the jaws on the bobbin less firm.

Referring to the second embodiment of the invention, Figs. 2 and 3, the shuttle 16, cavity 17, 15 spring jaws 18 and 19, cover 20, vertical bolt 21 and horizontal bolt 22 may be substantially the same as the corresponding parts above described, but the parallel notches are different. In this embodiment there are only three notches in each 20 jaw, the two outer notches 23 and 25 being of the same depth while the center notch 24 is relatively deeper and longer than the outer notches.

The filling carrier is comprised of a bobbin 26 having rings 27, 28 and 29 on the butt thereof. 25 These rings are formed of spring steel of circular cross-section and, as above, the distance between adjacent rings is materially less than the diameter of the stock of which they are formed. Unlike the embodiment first described, the rings 27, 30 28 and 29 may all have the same external diameter, but the center ring 28 still does not engage the spring jaws because of the large size of the center notches 24.

It will be apparent that the construction just 35 described can be used only where a three notch spring is acceptable. However, except for the limitation of the number of notches in the spring jaws this construction is obviously possessed of all the advantages enumerated above in connection with the embodiment of Figs. 1 and 4.

Having fully disclosed the preferred embodiments of my invention, I claim:

1. In a loom shuttle and filling carrier for 45 looms of the bobbin changing type, a shuttle body having a filling-carrier-receiving cavity therein, opposed spring jaws at one end of said cavity; and a filling carrier located in said cavity and having three circumferentially extending rings spaced along the butt thereof, the space between 50

adjacent rings being substantially narrower than the thickness of the rings, the two outer rings being engaged in and held by notches in said spring jaws and the center ring being free of said spring jaws.

80

2. In a loom shuttle and filling carrier for looms of the bobbin changing type, a shuttle body having a filling-carrier-receiving cavity therein, opposed spring jaws extending along opposite sides of said cavity at one end thereof, said jaws being provided with parallel holding notches extending transversely thereof; and a filling carrier located in said cavity, said filling carrier having three circumferentially extending rings spaced along the butt thereof, said rings being all of substantially the same thickness and the space between adjacent rings being substantially less than said thickness, the two outer rings only being engaged in and held by said notches and the center ring being free of said spring jaws.

90

3. In a loom shuttle and filling carrier for looms of the bobbin changing type, a shuttle body having a filling-carrier-receiving cavity therein, opposed spring jaws extending along opposite sides of said cavity at one end thereof, said jaws being provided with parallel holding notches of substantially uniform depth and extending transversely of the jaws; and a filling carrier located in said cavity, said filling carrier having three circumferentially extending rings spaced along the butt thereof, the space between adjacent rings being substantially narrower than the thickness of the rings, the two outer rings being engaged in and held by said notches and the center ring having a materially smaller external diameter 110 than either of said outer rings whereby said center ring can not be engaged in any of said notches.

105

4. As an article of manufacture, a filling carrier of the type adapted to be automatically transferred to a loom shuttle, said filling carrier having three circumferentially extending holding rings spaced along the butt thereof, said rings being all of substantially the same thickness and the space between adjacent rings being substantially less than said thickness, the two outer rings 120 having substantially the same external diameter and the center ring having a materially smaller external diameter than said outer rings.
